US00D913945S

(12) **United States Design Patent** (10) **Patent No.:** **US D913,945 S**
(45) **Date of Patent:** **** Mar. 23, 2021**

(54) **CONNECTOR FOR SIGNAL TRANSMISSION**(71) Applicant: **GigaLane Co., Ltd.**, Hwaseong-si (KR)(72) Inventors: **Kyung Hun Jung**, Hwaseong-si (KR);
Hwa Yoon Song, Hwaseong-si (KR);
Jin Uk Lee, Hwaseong-si (KR); **Hee seok Jung**, Hwaseong-si (KR); **Chang Hyun Yang**, Hwaseong-si (KR); **Sun Hwa Cha**, Hwaseong-si (KR); **Eun Jung Kim**, Hwaseong-si (KR)(73) Assignee: **GigaLane Co., Ltd.**, Hwaseong-si (KR)(**) Term: **15 Years**(21) Appl. No.: **35/507,401**(22) Filed: **Jan. 10, 2019**(80) **Hague Agreement Data**Int. Filing Date: **Jan. 10, 2019**Int. Reg. No.: **DM/202527**Int. Reg. Date: **Jan. 10, 2019**Int. Reg. Pub. Date: **Sep. 6, 2019**(30) **Foreign Application Priority Data**

Aug. 1, 2018 (KR) 30-2018-0035734
